UNITED STATES PATENT OFFICE.

DONALD MUNRO, OF BOOTLE, ENGLAND.

ELEVATING TRUCK.

Application filed January 21, 1921. Serial No. 438,900.

To all whom it may concern:

Be it known that I, DONALD MUNRO, a subject of the King of England, residing at 373 Hawthorne Road, Bootle, in the county 5 of Lancaster, England, have invented certain new and useful Improvements in Elevating Trucks, of which the following is a specification.

This invention relates to trucks, which 10 are used for lifting and transporting loads supported on platforms, the truck being shifted under the platform and then an elevating member forming a part of the truck raised to lift the load from the platform.

15 The present invention has for its object to provide a truck which shall be simple in construction, strong, and not liable to derangement under ordinary conditions of use.

Another feature of the invention is the 20 means, hereinafter described, whereby a hook or claw member pivotally mounted on a handle lever is caused to engage itself with and also release itself from a transverse portion of an elevator frame.

25 A further feature consists in a special construction of hydraulic check or dashpot.

I will further describe my invention with the aid of the accompanying sheets of explanatory drawings, in which:—

30 Fig. 1 is an elevation, partly in section, and Fig. 2 a plan of a truck embodying some of my improvements.

Fig. 3 is a detached view of the handle lever and pivotal hook or claw-like member.

35 Fig. 4 is a longitudinal section, drawn to an enlarged scale as compared with Figs. 1 and 2, of a hydraulic check or dashpot, Figs. 5 to 8 being detached details, and

40 Fig. 9 represents a modified form of handle lever, pivotal hook or claw member, and means whereby said hook or claw is caused to engage itself with and also release itself from the elevator frame.

Fig. 10 is a detail view of the platform 45 of a truck.

In the several views like characters of reference denote like or corresponding parts wherever they occur.

Referring now to the drawings, but first 50 more particularly to Figs. 1 to 8,

There is provided a base or platform 1 having integrally depending side or lateral extensions or members 1^a between which a pair of steering wheels 2, 2, are disposed. 55 Said wheels are mounted on axle members 3^a, 3^b, which are formed by turning down

the ends of a bar 3, and on which are pinned collars 4, 4, thus said wheels 2, 2, are free to rotate independently of one another. On said wheel carrier bar 3 there is disposed a 60 turn-table 5.

Extending through said bar 3, turntable 5 and a circular boss 1^b formed on the under-side of platform 1, and projecting above the top or face of said base or platform, is a 65 pin or spindle 6 on the lower end whereof a nut 6^a is fitted: by revolving said spindle 6 said turntable 5, axle carrying bar 3 and wheels 2, 2, may, if desired, be turned through a complete revolution. 70

Articulated with said wheel-actuating pin or spindle 6 by means of a transverse bolt 7 is the lower bifurcated end 8^a of a handle lever or arm 8, (hereinafter for convenience of reference designated "operating arm") 75 at the upper portion whereof there is fitted or formed a transverse handle. Pivotally connected by means of a pin 9 to the lower end 8^a of said operating arm is a hook or claw member 10 which is articulated to a rod 80 or bar 11 (Fig. 3)—on the upper end whereof a handle 11^a is formed or provided—by means of links 12 pivotally connected to the hook or claw 10 at 13 and to rod 11 at 14.

Said rod 11 is adapted to slide in suitable 85 guide loops 15 provided on said operating arm 8.

Secured to the depending side extensions 1^a, 1^b, of said base or platform 1 by means of bolts 16 and 25 are ends of longitudinal 90 frame members 17, 17, near and between the rear portions whereof are revolvably disposed upon a transversely arranged axle 18 a second pair of floor wheels 19, 19.

Disposed above said lower wheel-carrying 95 structure is an elevator frame 20, of substantially rectangular shape or configuration, between the longitudinal members whereof are transversely secured rods or bars 21, 22, which are connected by means of pairs of 100 side links 23, 23, 24, 24, respectively, to the lower frame structure at bolt 25 and the rear wheel axle 18. Rod 21 is secured to brackets 20^a bolted to the upper frame member 20 (said brackets also prevent the truck from 105 running too far under its platform) whilst the ends of rod 22 are secured directly to the frame 20. If, therefore, said claw member or hook 10 connected with said operating arm 8 is lowered into engagement with the 110 front transverse rod 21 of the upper elevator frame 20 and said operating arm 8 is pulled

forward and downward, said upper frame 20 will rise from the lower frame 17 in parallel fashion through said link connections. Said links 24 are prevented from lateral dis- 5 placement by collars 24^a secured to axle 18 and collars 24^b secured on rod 22.

Pivottally mounted on bolts 26, 26, extending through lugs 27, 27, cast on said base or platform 1, to which said lower 10 frame structure is attached, are a pair of longitudinally-arranged levers 28, 28, near the "nose" end of each of which is provided a slot, recess, or hook-like formation 29, and the other ends whereof are connected by 15 means of a foot rod or bar 30. The lever and bar constitute a pivoted keeper adapted to hold the frame 20 elevated.

Disposed on the underside of each lever—being let into suitable sockets of the base 20 or platform 1—is a coiled compression spring 1^c which tend to force the hooked arms of said levers downwards.

In use, to elevate the upper frame structure 20, said operating arm 8 is moved to 25 the vertical position, and the claw or hook 10 carried thereby is depressed to its lowermost position by means of rod 11; said operating arm 8 is now pulled forward and downward, in which action said claw or 30 hook 10 engages with and pulls the adjacent transverse rod or bar 21 of the upper frame 20, so that—through the link connections referred to—said upper frame 20 is raised above and parallel to the lower frame structure; simultaneously said bar 21 of the upper frame displaces the levers 28, 28, against 35 the resistance of springs 1^c, and moves into register or alignment with the slots 29 thereof: said levers 28, under the influence of 40 the springs 1^c, enter into locking engagement with the bar 21, thus securely maintaining the upper frame 20 in its raised or operative position. The lifting hook or 45 claw 10 is now pulled up by means of handle 11^a, and the truck is controlled by the operating arm 8.

Prior to the raising of the upper frame 20 the truck will be run under a suitably constructed platform supporting the load in 50 well-known manner.

To lower the load, the operator places his or her foot on said transverse foot rod or bar 30 and depresses same, in which action the front arms of said longitudinal levers 55 28, 28, rise—against the resistance of said springs 1^c—out of engagement with, and so releasing the adjacent transverse upper frame bar 21; said upper frame then falls by gravity.

60 In order to prevent shock on the lowering of a load, there may be provided a hydraulic check or dash-pot, or other damping device or devices, disposed between the lower wheel-carrying structure and the upper elevator 65 frame.

In constructing the check or dash-pot illustrated there is provided a cylinder 31 on one end whereof is formed a cap or closure 31^a which is sweated to a transverse member 32 the ends 33 whereof are revolvably disposed 70 in plates 34 bolted to the longitudinal members of the lower frame 17.

Extending through the other ends of said cylinder 31 is a tubular plunger 35 which forms an extension of a transverse tubular member 36 the reduced ends 37 of which are pivotally disposed in end plates 38 secured to the upper frame structure 20. Within a recess of said cylinder 31 packing rings 39 are disposed, said rings being maintained in position by the screw cap piece 40. Secured in the enlarged inner end of said plunger 35 is an apertured plate 41 and the head 42 of a valve 42, 42^a, which is normally maintained on its seat by means of a spring 43 positioned between a boss 41^a formed on the plate 41 and an extension 42^b of the valve 42, 42^a. Oil is supplied to said device by being poured through a passage in the tubular member 36 and normally closed by screw 90 plug 44. When the upper frame 20 is raised the outward displacement of the plunger 35 causes the valve 42, 42^a, to open against the resistance of its spring 43, and oil flows through the apertures 41^b of plate 41 to the inner end of the cylinder 31. When the upper frame is released the valve 42, 42^a, closes and the oil returns through a by-pass 45 formed in the head 42 of valve; said frame 100 95 100 thus settling down gently on the lower frame 17.

Referring now to the lever constructions shown in Fig. 9, a rod 46 is pivotally connected at 13 to the hook or claw 10 and extends through a guide collar 15 secured to arm 8. Between the upper face of said collar 15 and a stop collar 47 a helically coiled wire spring 48 is disposed around rod 46, and between the lower face of said collar 15 and a stop collar 49 a helically coiled wire 110 spring 50 is disposed around said rod.

In use, on the operating arm 8 being moved into vertical position to engage transverse member 21 of the upper elevator frame 20 the nose of said hook or claw member 10 meets said member 21, and in its engaging operation, rises, in which action the rod 46 is pulled downwardly, thereby compressing spring 48, so that the engagement of claw 10 with said transverse member 21 is effected 120 and maintained under the influence of said spring 48. When claw 10 has brought the transverse member 21 into locking engagement with the levers 28, 28, the consequential upward movement of the rod 46 has 125 compressed spring 50 with the result that on the downward pressure on said arm 8 said spring 50 causes the hook or claw member 10 to rise out of engagement with said transverse member 21.

Having now described my invention, what I claim as new and desire to secure by Letters Patent is:—

1. A truck comprising a wheel supported structure, an elevator frame on said wheel supported structure and adapted to be raised and lowered relative thereto, means connecting said elevator structure to said wheel supported structure adapted to cushion movement of said elevator structure relative to said wheel supported structure, a platform at the forward end of said wheel supported structure, a steering handle pivotally connected to said platform, a claw member pivotally connected to said steering handle, a transverse member carried by said elevator structure and adapted to be engaged by said claw member so that said steering handle may be manipulated to raise said elevator structure relative to said wheel supported

structure, a pivoted keeper on said platform adapted to automatically engage the transverse member of said elevator structure and hold said structure in a raised position, and means extending along said steering handle and connected to said claw member adapted for shifting said member relative to said steering handle.

2. A truck as called for in claim 1, where-in said keeper has a treadle and springs are mounted in said platform normally engaging said keeper to cause said keeper to snap into engagement with the transverse member of said elevator structure.

In testimony whereof I affix my signature in the presence of two witnesses.

DONALD MUNRO.
